UNITED STATES PATENT OFFICE.

EDWARD MILLS, OF WHITINSVILLE, MASSACHUSETTS, ASSIGNOR TO WHITIN MANUFACTURING WORKS, OF WHITINSVILLE, MASSACHUSETTS, A CORPORATION OF MASSACHUSETTS.

ATTACHMENT FOR COTTON LAPERS.

Application filed January 22, 1927. Serial No. 162,907.

This invention relates to improvements in machines which form their production into laps for use in subsequent processes. Prior to the date of my invention it was necessary in machines of this kind for the operator to impart motion by hand or foot to a lever to bring the operative gears into mesh to resume thelapping process after it was interrupted for the removal of a previously formed lap.

The object of my invention is to provide automatic means for bringing the operative gears into mesh thus facilitating the movements of the operator in his duties about the machine.

A preferred form of my invention is illustrated in the accompanying drawings in which—Figure 1 is a side elevation of alapping machine showing my invention attached thereto.

Figure 2 is an end elevation of a fragmentary part of alapping machine showing the relation of the various parts of my invention when a full lap has been removed and a new one ready to be started.

Figure 3 is a view similar to Figure 2 showing the relation of the parts of my attachments while the lap is being formed.

Figure 4 is an end view of the full-lap knock-off motion.

Figure 5 is an end elevation of alapping machine showing in connection with Figure 1 the gearing for imparting motion to the rotative member of my attachment.

Referring to the drawings 10 designates the sides of alapping machine such as usually used for forming laps from fibre delivered by a picking machine, 11 and 12 are lap winding rolls which effect the winding 40 of the lap 13 on its pin 14. The lap winding rolls have a slow continuous rotary motion derived through a train of gears from the usual cross shaft, 15, of the picking machines 16 a fragmentary portion of which 45 is shown in Figure 1. A drop-lever 17 fulcrumed at 18 supports a bearing of the drop-shaft 19 which is continuously rotated by the gearing from the shaft 15. By this construction when the drop-lever is in its elevated position the lap starting operative pinion 20 fixed to the drop-shaft meshes

with the gear 21 driving the calender roll 22 and thus the sheet of fibre is delivered to the lap winding rolls. A depression of the drop-lever disengages the driving means of the calender roll and thus the delivery of the fibre ceases. A trip-lever 23 has a shoulder 24 adapted to engage the drop-lever and holds it in its elevated position with the operative gears in mesh. When the lap 55 becomes full the knock-off motion pawl 25 suitably rotated from the calender roll pushes the trip-lever 23 out of engagement with the drop-arm 17 which then drops by gravity thus disengaging the pinion 20 from 60 its meshing relation with the calendar roll gear with the result of stopping further delivery of the calender roll.

The trip-lever 23 and drop-lever 17 are each provided with a handle whereby they 70 may be manually actuated if occasion requires before the lap becomes full and ready for removal.

All of the above is descriptive of alapping machine lap starting mechanism of ordinary 75 construction and as such is not claimed as my invention except in combination of certain novel features whereby the starting of a new lap is automatically accomplished.

In accordance with the present invention 80 when the lap has attained its full diameter the knock-off pawl 25 pushes the trip-lever over so that the drop-arm 17 falls and thus disengages the operative gearing; the operator then pulls out the lap pin 14 and lays 85 it in holders, one of which 38 is fixed to the frame of the machine and the other is on the upper end of the weighted lever 26 swingable on a fulcrum 27 fixed to the machine frame. The lower end of the lever 26 90 coacts with a lug 28 on the inner end of the member 29 slidably and swingably mounted on a shaft 30 in a fixed relation with the machine frame. The outer end of the member 29 is provided with a cam shaped member 31 adapted to cooperate with the drop-lever to lift the operative gearing into engagement. An upright finger 32 fixedly connected to the sliding member 29 coacts with a roll 33 fixed to the face of a disk fastened 95 to journal 34 of the lap winding roll 11 whereby the rotary movement of the disk 100

causes the roll to act with much force on the leverage of the finger 32 thus causing the cam 31 to swing upward against the underside of the drop-arm sufficiently high to bring the drop shaft pinion 20 into mesh with the calender roll gear 21 and thus starts the formation of a new lap.

The amount of the swinging movements of the members 26 and 29 are controlled by 10 adjustable abutting screws 35 and 36 respectively.

In operation while the lap is being wound the position of various members of my invention are as shown in Figure 3, the finger 15 32 being clear of the path of its actuating roll 33 and the drop-arm in its highest position with the operative gearing in mesh. When the knock-off motion indicates that the lap is full by releasing the drop-arm 20 and thus stopping the delivery of the calender roll, the operator pulls the lap pin from the lap and lays the pin on the holding lever, the weight of the empty pin being sufficient to cause the holder lever 26 to 25 swing on its fulcrum and by suitable connections slides the actuating finger 32 into the path of the roll 33 whereby the drop-arm is slowly raised until the operative gearing mesh, the time taken to do this being sufficient for allowing the operator to take the 30 lap pin from its holders and place in proper position on the lap winding rolls for the formation of a new lap. After the empty lap pin is taken from its holders the various 35 members resume their normal positions due to the influence of the counter balancing weight 37 acting on the holder lever 26.

I claim:

1. In a machine of the character specified, 40 the combination of a drop-lever, a fulcrum on which said lever is swingable, a driving pinion supported by said lever, a calender roll, a driven gear attached to the calender roll and adapted to mesh with the driving 45 pinion, a trip-lever coacting with the drop-lever normally maintaining the operative gears in mesh, means when the lap is full for automatically releasing the trip-lever thus disengaging the operative gear- 50 ing and means whereby said drop-lever is

automatically raised thus bringing the operative gears again into engagement.

2. In a machine of the character specified, the combination of a drop-lever, a fulcrum on which said lever is swingable, a driving 55 pinion supported by said lever, a calender roll, a driven gear attached to the calender roll and adapted to mesh with the driving pinion, a trip-lever coacting with the drop-lever normally maintaining the operative 60 gears in mesh, means for automatically releasing the trip-lever when a lap is full thus disengaging the operative gearing, a pair of lap winding rolls, a pin on which the lap is wound, and automatic means actuated by 65 the weight of an empty lap pin to effect the lifting of the drop-lever thus bringing the operative gearing again into engagement.

3. In a machine of the character specified, the combination of a drop-lever, a fulcrum on which said lever is swingable, a driving 70 pinion supported by said lever, a calender roll, a driven gear fixed to the calender roll and adapted to mesh with the driving pinion, a trip-lever coacting with the drop-lever normally maintaining the operative 75 gears in mesh, means for automatically releasing the trip-lever when a lap is full thus disengaging the operative gearings, a pair of lap winding rolls, a pin on which the lap is wound, a lever supporting one end of an empty lap pin and swingably actuated by the 80 weight of said lap pin, a fulcrum for said lever fixed to the machine frame, counter-balancing means for said lever, a sliding 85 member swingably mounted on a shaft in a fixed relation to the machine frame, coacting connections between said lever and the sliding member, a cam member fixed to said sliding member and adapted to coact with the underside of the drop-lever to raise the 90 same, an upright finger in a fixed relation with said sliding member, and a roll eccentrically connected to the journal and adapted to coact with said finger to actuate said cam thus automatically bringing the operative 95 gearing again into engagement.

In testimony whereof, I have signed this specification.

EDWARD MILLS.
